UNITED STATES PATENT OFFICE.

EARL G. WATROUS, OF CHICAGO, ILLINOIS.

LAVATORY WASTE.

Application filed December 27, 1921. Serial No. 525,071.

To all whom it may concern:

Be it known that I, EARL G. WATROUS, a citizen of the United States, residing at Chicago, in the county of Cook and State 5 of Illinois, have invented certain new and useful Improvements in Lavatory Wastes, of which the following is a specification.

This invention relates to closure devices or valves for the drains of basins, wash 10 bowls and the like, and more particularly to devices of this character having pop-up valves or closures with means for operating the same. The objects of the present invention are to provide a device of this character having novel actuating means for raising and lowering the valve or plug; to provide a spring controlled lever which may be operated by a push rod and which will hold the valve in either raised or lowered position; and in general to provide such improved features and details of construction as will appear more fully from the following description:

In the accompanying drawings illustrating this device:

Figure 1 is a sectional view of a portion of the lavatory with the waste shown in position;

Figure 2 is an enlarged horizontal sectional view of the operating lever and connected parts; and

Figure 3 is an enlarged sectional view of the waste or drain pipe with the valve or stopper shown in position.

The bowl or basin 4 which may be of any ordinary or preferred construction is provided with the usual waste pipe 5 having outlet holes 6. This pipe is threaded to receive a coupling and lever supporting member 7 which engages with the lower end of the same and coacts with a washer 8 of suitable material to make a tight closure. The valve or stopper 9 has a downwardly projecting stem 10 which is preferably provided with wings 11 which engage with the waste pipe 5 for guiding the stem. The lower end of the stem 10 has one or more holes 12 which are adapted to be engaged by the inner end 13 of an operating lever 14. This lever has a substantially semi-spherical bearing 15 which engages with a similarly shaped socket 16 in a plug 17 which is screwed into the outer end of a chamber or projection 18 on the coupling 7. This forms 55 a substantially ball and socket joint which may be provided with a bushing 19 if de-

sired to make the joint tight. The lever 14 also has a bearing 20 for engagement with one end of a spring 21 which is preferably of conical form and surrounds the inner 60 arm 13 of the lever which swings up and down within the spring. The base of the spring 21 is preferably seated in a flanged ring 22 which engages with a bearing 23 in the end of the chamber 18. The bearings 65 20 and 23 are preferably of the knife edge type so that the spring will rock freely on the same. The end of the chamber 18 has a slot 24 to permit the vertical movement of the end of the lever. The opposite end 70 of the lever 14 engages with a bearing 25 on a sleeve or collar 26 which fits over the lower end of an operating rod 27. The end of the lever is held in position on the bearing and the sleeve is also secured in adjusted position by means of a set screw 28 which passes through the bearing and engages with the rod 27 as shown in Figure 2. The rod 27 passes up through a guide or supporting member 28' at the top of the basin 4 and is 75 provided with a knob or handle 29 for convenience in operating the same. The rod 27 is preferably bent or offset so that the lower end is somewhat out of alignment with the upper portion. This is done for 80 the purpose of enabling the parts to be used with bowls or lavatories where the horizontal distance between the axis of the guide 28' and the axis of the valve stem 10 is varied. The parts are shown in Figure 1 in 85 the position for the greatest distance between these parts. If this distance were less the rod 27 could be swung around and the lever 14 with its supporting parts also 90 swung around to a corresponding position 95 which would allow the connection to be made for such shorter distance.

The operation of the device will be readily understood from the illustration shown in Figure 1. When the valve is to be opened, 100 the handle 29 is pressed downwardly and swings the lever 14 until the inner end 13 passes the deadcenter, whereupon the spring 21 which has been compressed by this movement, will expand and will throw the inner end of the lever upwardly or hold it in raised position. The inner end of the lever acting on the valve stem 10 will raise the valve and hold it in open position. It will be noted that the waste pipe 5 is threaded 105 so as to allow the coupling 7 to be adjusted for bowls having different thicknesses at the

bottom and the holes 12 in the valve stem will permit the lever 14 to be adjusted for different positions of the coupling. The arrangement of the conical spring 21 over the inner end of the lever permits the spring to act as one member or arm of a toggle and thereby simplifies the construction and increases the efficiency of operation.

As plumbing fixtures are made in various shapes and styles it will be apparent that this device may be changed in details of construction and arrangement of parts without departing from the scope of this invention and therefore I do not wish to be limited to the exact construction shown and described other than as specified in the following claims.

I claim—

1. In a lavatory waste, the combination with a stopper having a downwardly projecting stem, of a lever coacting with said stem for raising and lowering the same, a conical spring fitting over said lever and adapted to hold it in raised or lowered positions and means for actuating the lever.

2. The combination with a waste stopper having a downwardly projecting stem, of a lever pivoted adjacent to said stem and having one end engaging therewith, a conical spring arranged over the lever and having one end engaging with a bearing on the lever, a fixed abutment for the opposite end of the spring and a push rod connected with the lever for oscillating the same.

3. A lavatory waste construction comprising a waste pipe, a valve fitting in said pipe and having a downwardly projecting stem, a connection threaded to said pipe, a lateral chamber in said connection, a lever having a ball and socket pivot in the outer end of the chamber and having one arm engaging with the stem, an overthrow spring in said chamber adapted to act on the lever to hold the lever in raised or lowered position only and means for actuating the lever.

4. A device of the character set forth comprising a drain pipe for a lavatory bowl, a second pipe threaded to engage with the drain pipe and adapted to make a closure at the bottom of the bowl, a valve for said drain pipe, a downwardly projecting stem from said valve, a spring actuated overthrow lever adjustably connected with said stem, a push rod pivotally connected with said

lever, a guide for said push rod, the lower end of the push rod being offset for the purpose described.

5. In a device of the character set forth, the combination of an operating rod, a sleeve on said rod having a lateral bearing, a lever engaging the said bearing and a set screw through the bearing, said set screw serving to hold the sleeve in position on the rod and also serving to hold the end of the lever in engagement with the bearing.

6. In a waste construction, the combination of a waste pipe, a valve fitting in said pipe, a stem for said valve having lateral guides engaging with the pipe, and having a plurality of holes in the lower end thereof, a coupling member engaging with said pipe and having a lateral chamber, a lever pivoted in said chamber and adapted to engage with said stem, a compression spring coacting with the lever for holding it in raised and lowered positions only and a vertically movable operating rod pivotally connected with the outer end of the lever.

7. A device for operating a waste valve having a valve rod comprising a pivoted lever adapted to engage with the valve rod and having a bearing adjacent to the pivot, a conical spring around said lever with its small end engaging with said bearing and an abutment for the opposite end of the spring, the arrangement being such that the spring acts as one member of a toggle and serves to hold the lever in adjusted position.

8. The combination with a lavatory, of a drain pipe, a coupling threaded to engage said pipe, a packing between the coupling and the bottom of the lavatory, a valve in said pipe, a stem projecting downwardly from the valve, a lateral chamber in said coupling having a plug with a substantially hemispherical seat therein, a lever having a bearing engaging with said seat and projecting inwardly through the chamber and engaging with the valve stem, a conical spring over said lever, one end of the spring engaging with the lever and the opposite end with a bearing in the chamber, a guide in said lavatory, an operating rod fitting in said guide and having an offset at the lower end which is pivotally connected with the outer end of said lever.

EARL G. WATROUS.
